UNITED STATES PATENT OFFICE.

FRANK R. SINNING, OF RAMSEY, ILLINOIS, ASSIGNOR TO FREDERICK HACHMANN, OF CHICAGO, ILLINOIS.

TRACK-ALIGNING JACK.

Application filed August 20, 1923. Serial No. 658,212.

This invention relates to a track aligning jack of that type designed to engage the edge of the lower flange of a rail and exert a lateral strain thereagainst for shifting the 5 rail or aligning the same with other rails.

It is an object of this invention to provide a jack which can be laterally shifted so that a wider range of movement may be imparted to the object to be shifted.

10 It is also an object of this invention to provide a stationary base and a support for the jack which may be adjustably anchored to the base in different positions.

15 With these and other objects in view, which will become more apparent in the following description and disclosures in the drawings, this invention comprises the novel mechanism and combinations hereinafter described and more particularly pointed out 20 and defined in the appended claims.

25 In the accompanying drawings, which illustrate a preferred embodiment of this invention, and in which similar reference numerals refer to similar features in the different views:

Figure 1 is an elevational view of the jack adjacent a railroad rail which is shown in section.

30 Figure 2 is a front enlarged elevational view of the jack.

Figure 3 is an enlarged view taken substantially upon the line 3—3 of Figure 2.

Figure 4 is a bottom plan view of the adjustable jack support or carrier.

35 Figure 5 is an enlarged section upon the line 5—5 of Figure 2 and showing the section of a railroad rail adjacent thereto.

Figure 6 is an enlarged plan view of the base.

40 Figure 7 is an enlarged section upon the line 7—7 of Figure 5.

As shown on the drawings:

45 In referring now to the drawings, which illustrate the chosen embodiment of this invention, there is illustrated a base 1 having anchoring tangs 2 projecting from the bottom thereof. Said base is relatively long and narrow and its longitudinal marginal edges are inturned in the form of overhanging flanges 3 whereby lateral marginal grooves or guideways are formed. Between these guideways, the base is provided with a series of ratchet teeth 4 which slope forwardly upon the rear face, the front faces

thereof being substantially perpendicular to 55 the base.

A jack lever supporting shoe or carrier member 5 is slidably supported upon the base 1. This carrier member preferably consists of an integral casting having a bottom 6, lateral upstanding ears or wings 7 and transverse portions 8 and 9, the latter of which forms a forwardly open faced socket in which a jack lever 10 is pivotally supported. This jack lever is provided with a 65 vertical socket for receiving an operating handle. The jack lever has a downwardly extending and forwardly projecting serrated toe 10^a which is adapted to engage against the lateral surface of an object such 70 as the illustrated railroad rail for laterally adjusting the same. The lower surface of the shoe is provided with a longitudinally extending groove 11 for accommodating the ratchet teeth 4 on the base, and the forward 75 lateral margins of the shoe having laterally projecting lugs or trunnions 12 which slidably fit in the guideways of the base. The upper and lower surfaces of these trunnions are slightly arcuate in longitudinal direction so that the rear of the shoe can be slightly rocked or elevated to raise the ratchet tooth or pawl 13 projecting from the lower rear portion of the shoe out of engagement with the ratchet teeth 4 so that the 80 shoe may be longitudinally adjusted on the base. This pawl 13 is of course shaped so as to fit the teeth 4 so that when in engagement therewith the shoe or carrier 5 will be anchored against rearward shifting movement during the operation of the jack lever. 85

In using this jack, the same is positioned against the object to be shifted or adjusted, and the jack lever is operated so that the toe 10^a will engage the object for shifting the 90 same. In using this jack as a rail aligner, for which it is primarily designed, the base member 1 is positioned under a rail so that the toe 10^a may engage the lower flange thereof. By exerting rearward pressure 100 upon the handle of the lever the rail will be forced in a lateral direction to align the same with the other rails. If the swing of the jack lever is not sufficient to effect the desired lateral movement of the rail, the lever 105 may be released and the rear end of the shoe or carrier 5 may be elevated to raise the pawl 13 above the ratchet teeth 4 so that the

shoe or carrier may be shifted forward any desired distance so that the jack lever will be brought near enough to the rail again to effect a second operation thereof. Any 5 number of such adjustments of the carrier may be made as is necessary to shift the rail the desired amount, as is obvious.

It will be appreciated that in using an adjustable carrier for the jack lever, it is not 10 necessary to tear up the base and reposition the same when more than one throw of the lever is required to shift the rail. By making the carrier adjustable, much time and labor is saved in shifting objects requiring 15 more than one throw of the lever.

I am aware that numerous details of construction may be varied through a wide range without departing from the principles of this invention, and I therefore do not 20 purpose limiting the patent granted otherwise than necessitated by the prior art.

I claim as my invention:

1. In a track aligning jack, a base member having anchoring tangs projecting from the 25 lower surface and having inturned marginal flanges upon its upper surface to provide guideways and ratchet teeth between said guideways, a jack carrier having laterally projecting trunnions supported on said

base with said trunnions in said guideways, and having a ratchet tooth adapted for engagement with said ratchet teeth on said base, and a swingable jack lever pivoted in said carrier. 30

2. In a track aligning jack, a base having lateral guiding means, a jack lever supporting member having trunnions slideable and tilttable with respect to said guiding means, and interlocking means between said base and member. 35

3. In a track aligning jack, a base having inwardly opening marginal grooves, a jack lever support having means extending into said grooves, said means being so constructed as to provide rockers for said support and interlocking means between said base and carrier controlled by rocking movements of the latter. 45

4. In a track aligning jack, a base, a jack lever support slidably and tiltably mounted upon said base, means for retaining and guiding said support, and interlocking means between said base and support controlled by the tilting movement of the latter. 50

In testimony whereof I have hereunto 55 subscribed my name.

FRANK R. SINNING.
